UNITED STATES PATENT OFFICE.

WILLIAM C. BROADWELL, OF NEW YORK, N. Y.

SEPARATOR.

Application filed March 3, 1923. Serial No. 622,498.

This invention relates to separators particularly of the ash sifter type designed to receive an ash pan or receptacle which is carried bodily in a circular path about the axis of a rotatable screen adapted to receive the ashes which are caused to travel over the surface thereof as the screen is rotated, thereby separating the unburned fuel from the ashes which are allowed to pass from the machine into the usual ash receiving receptacle, whereas the unburned fuel is deposited back into the pan upon the completion of each screening or separating cycle in the operation of the machine.

An important object of my invention is to provide in a device of the character mentioned an improved and simplified means for automatically locking the pan in a fixed position within the machine at the beginning of each screening or separating operation.

A further object of the invention is to provide a means for retaining the pan locking means against reverse movement with respect to the rotatable screen except at such time as the screen is maintained in its normal position at rest.

Another object of the invention is to provide in combination with the rotatable screen a means for facilitating a correct positioning of the pan within the machine to insure reliability in the emptying of ashes from the pan and in the depositing of reclaimed fuel thereinto.

Other objects and certain advantages of the invention will become apparent from the following description when taken in connection with the accompanying drawings in which—

Figure 1 is a front elevation of the machine embodying my invention.

Figure 2 is a horizontal sectional view taken on line 2—2 of Figure 1, the rotatable screen and certain other cooperative elements being shown in elevation.

Figure 3 is a vertical sectional view taken on line 3—3 of Figure 1.

Figure 4 is a perspective view of an improved type of ash pan particularly adapted to be used in connection with the machine embodying my invention.

Figure 5 is a fragmental sectional view taken on line 5—5 of Figure 4.

Figure 6 is a fragmental sectional view illustrating the position of a closure when locked in its open position.

In the drawings wherein for the purpose of illustration is shown what I at present consider the preferred form of my invention the numeral 5 indicates a casing or housing within which the various cooperative elements embodying my invention and hereinafter more particularly referred to are located. This housing is constructed from sheet metal and comprises end members 6 having inwardly turned flanges 7, the lower ends of the end members 6 being inclined as shown most clearly in Figure 1, and suitably connected to a base 8 which constitutes a cover for the usual ash receptacle, not shown, into which the ashes are adapted to pass from the machine. In addition to the flanges 7 the end members 6 are provided adjacent thereto with depressions or grooves 9 into which is fitted a sheet metal cover 10, the sheet metal cover being connected to the base 8 and locked in position with respect thereto by means of flanges 11 adapted to engage the under face or side of the base adjacent a relatively large opening 12 formed therein through which the sifted ashes are adapted to pass as above mentioned. The cover 10 and end members 6 when assembled as shown in Figures 1, 2 and 3 are retained properly positioned in a dust-proof unitary structure by means of transversely disposed tie-rods or bolts 13 provided at opposite ends with nuts 14. It will be noted that, from the way in which I have constructed and assembled the cover 10 and end members 6, the tie-rods or bolts 13 constitute the only means which it is necessary to employ for retaining the elements of the housing 5 in an assembled relation and that by reason of this construction the assembling of the device as a whole may be carried out expeditiously in the process of manufacture.

In the cover 10 there is cut or otherwise provided an opening 15 over which is fitted a closure 16. This closure is bent to conform to the contour of the cover 10 and at one longitudinal edge thereof is folded upon itself as shown at 17 to provide an elongated opening 18 through which is passed a transversely disposed hinge rod 19 suitably connected to the housing 5 as by means of brackets 20. By reason of this construction the closure 16 is adapted to permit of a sliding movement with respect to the cover 10 in order to free the inwardly turned lip 21

from engagement with the inner face of the cover 10 adjacent the opening 15 so that it may thereafter be swung about the hinge rod 19 as a pivot to its open position. After 5 lifting the closure 16 to the dotted line position shown in Figure 3 it may be so dropped or lowered that the hinge rod 19 will occupy a position within the opening 18 as shown in Figure 6. From the foregoing it will be 10 appreciated that the inwardly turned lip 21 functions to retain the closure 16 in intimate engagement with the cover 10 when closed and that the peculiar construction which I employ at the opposite longitudinal edge of 15 the closure so functions in a cooperative manner with the transversely disposed hinge rod 19 as to effectively retain the closure in its open position shown in Figure 6.

To the end members 6 there is journaled 20 a transversely disposed shaft 22 which extends throughout the length of the housing and is provided at one end with a crank 23. Upon the shaft 22 there is supported a 25 rotatable sifter or separator unit indicated as a whole by the numeral 24. This unit is free to rotate to a certain extent with respect to the shaft 22 as will hereinafter more readily appear and comprises side members 25 provided with flanges 26 and 27. To the flange 26 there is suitably connected a base or bottom 28 adapted to receive thereupon the usual ash pan or receptacle 29 or one of the 30 type shown in Figure 4 which is indicated by the numeral 30 and will be more particularly described hereinafter. The base or bottom 28 is bent at right angles to provide an abutment 30 which is spaced an appreciable distance from the flange 27 and functions as a means for enabling one to 35 properly position the ash pan 29 within the machine. To the side members 25 are connected a pair of converging screen supporting elements 31 provided at spaced intervals with ears or lips 32 which are adapted to 40 function as means for retaining a screen 33 permanently attached to the converging elements 31 at their respective outer edges.

In order to lock the ash pan 29 in position 45 upon the base or bottom 28 to prevent the same from being displaced during the operation of the machine I provide a clamping arm 34 which is secured to the shaft 22 and adapted to rotate therewith. The shaft 22 is provided also with an auxiliary locking 50 element in the form of a fork 35 having converging legs 36 both of which are adapted to engage the bottom of the pan 29 simultaneously with the engagement of the arm 34 therewith. In order to prevent the pan 55 29 from moving laterally in a rearwardly direction I provide the arm 34 with a finger 60 37 which is adapted to engage one side of the pan as shown in Figure 3 and retain the same in intimate engagement with the abutment 65 30. It will be appreciated therefore

that with the ash pan 29 so engaged and positioned as shown in Figure 3 the same will be maintained against movement in all directions with respect to the vase or bottom 28 when the sifting or separator unit 24 is rotated.

In order to restrain, to a certain extent, movement of the separator unit so that the arm 34 and auxiliary clamping element 35 will penetrate the ashes and engage the bottom of the pan 29 before the separator unit begins to rotate, I provide a friction brake indicated as a whole by the numeral 38. This brake comprises a drum 39 which is fastened to one of the side members 25 and is engaged by a friction band 40 adapted to be anchored to some stationary part of the apparatus such, for example, as one of the end members 6. The brake not only serves to restrain the separator unit against rotation at the beginning of the sifting operation but also functions as a means for preventing the separator unit from rotating with respect to the shaft 22 after the pan has been elevated to its maximum height 50 and has started on its downward course. By such an arrangement it will be appreciated that the arm 34 and auxiliary clamping element 35 will always be maintained in firm engagement with the bottom of the pan 29 during the rotation of the shaft 22 regardless of the position assumed by the pan in the operation of the machine.

In the type of apparatus embodying my invention it is necessary to prevent a reverse movement of the shaft 22 during the rotation of the separator unit 24 and to accomplish this desired object I provide the shaft 22 with a ratchet 41 adapted to cooperate with a pawl 42 pivotally connected to one of the end members 6. At the completion of the sifting operation it is necessary, however, to reverse the rotation of the shaft 22 in order that the arm 34 and auxiliary clamping element 35 may be disengaged 100 from the bottom of the pan 29 to permit the same to be removed from the apparatus, and in order to be able to accomplish this reverse movement of the shaft 22 I have provided the separator unit 24 with a pin 43 which is adapted to engage and lift the pawl 42 free from engagement with the ratchet 41 upon the completion of a sifting operation. With the pawl 42 disengaged 105 from its cooperate ratchet 41, as shown in Figure 3, the shaft 22, as will be appreciated, may be so rotated as to lift the arm 34 and auxiliary clamping element 35 from engagement with the bottom of the pan 29 thus permitting the same to be readily removed from the apparatus.

In order to temporarily maintain the separator unit 24 in its normal position shown in Figure 3 upon the completion of the sifting operation, I have provided a spring 110

pawl 44 suitably connected to one of the members 6. This pawl is adapted to co-operate with lugs or stops 45 struck up from one of the side members 25, the pawl 44 being so constructed that its free end is adapted to assume a position intermediate these lugs. When the separator unit 24 is rotated in the direction of the arrow shown in Figure 3 the free end of the pawl 44 rides over the lowermost lug 45 and as the separator unit is further rotated the free end of the pawl 44 is permitted to ride over the uppermost lug 45 and assume the position shown in Figure 3. It will be appreciated from the construction of this temporary restraining means that the separator unit is, when being moved from its position of rest shown in Figure 3 in the direction of the arrow, temporarily restrained until such time as the pawl 44 has passed over the lowermost lug 45 whereas on the other hand the separator unit is positively prevented from rotation in a direction opposite to that shown by the arrow in Figure 3 when the separator unit is maintained in its normal position shown in Figure 3.

If desired the conventional type of ash pan 29 shown in Figure 3 may be dispensed with and the specially constructed type of pan 30 shown in Figure 4 substituted in lieu thereof. With the type of pan shown in Figure 4 it is possible to so adjust the same that when placed in the ash-pit of a furnace all, or substantially all, of the ashes dropping from the grate may be deposited therein after which its sides may be so retracted as to permit the same to be withdrawn through the opening of the furnace leading into the ash-pit the width or diameter of which, in some instances, is greater than the width of the opening or door. The particular form of pan 30 comprises a bottom 46 having end members 47 formed integral therewith, the end members being bent over at their outer ends to provide guards 49 within each of which are adapted to operate a pair of racks 50 and 51. These racks are adapted to cooperate with pinions 52 carried at opposite ends of a longitudinally disposed shaft 53 journaled in the ends 47, the shaft being provided with a handle 54. To opposite longitudinal edges of the bottom 46 are hingedly connected movable side members 55 carrying at opposite ends wings 56 which are pivotally connected to the several racks 50 and 51. If the door or opening leading into the ash-pit is too narrow to receive the pan 30 with its side members 55 extended as shown in Figure 4, the shaft 53 may be so rotated as to retract the sides 55 thus permitting insertion of the pan after which the shaft 53 is so rotated as to cause the side members 55 to assume their respective positions shown in Figure 4. When it becomes neces-

sary to remove the pan from the ash-pit the side members 55 are again retracted through the instrumentality of the shaft 53, the cooperating pinions 52 and racks 50 and 51. The pan 30 may then be placed within the apparatus and positioned similarly to the conventional form of pan 29 above mentioned.

By reason of the fact that the converging screen supporting elements or separator unit side members 25 are arranged in a converging relation with respect to each other, it follows that the relatively large particles of material, which are separated from the finer particles in passing laterally over the screen 33, are brought together upon the relatively narrow end of the screen 33 and are thereafter deposited upon a chute 57 from which they are directed upon a completed or substantially completed revolution of the separator unit 24 back into the receptacle at a given distance from the abutment 30. This distance is such that, regardless of the shape or size of the pans which might be employed, the reclaimed particles will, under all conditions, incident to the operation of the machine, be deposited back into the same. This constitutes a very important feature of my invention, for the reason that by so constructing certain elements of the device as to accomplish this desired object, I am enabled to subject the ashes of each individual pan to the necessary separating operation without transferring such ashes from one receptacle to another as would otherwise be necessary.

Regardless of the type of pan employed the operation of the apparatus is as follows: The shaft 22 is rotated in the direction of the arrow shown in Figure 3 and by reason of the fact that the separator unit 24 is at first restrained against rotation by the brake 38 and pawl 44 the arm 34 and auxiliary clamping element 35 will penetrate the ashes and engage the bottom of the pan after which the separator unit 24 is caused to rotate in the direction of the arrow shown in Figure 3. As the pan is elevated its contents are deposited upon the screen 33 and as the ashes travel over this screen the finer portions are permitted to pass through the mesh and escape into the usual ash receptacle, not shown, through the opening 12, the larger ash particles or unburned fuel being retained upon the screen 33 and upon reaching the end of the same are deposited upon the chute 57 which is secured to the converging side members 31 and to which the screen 33 is attached as by means of ears or lugs 58. The larger particles or unburned fuel upon being deposited upon the chute 57 are directed centrally or substantially centrally back into the pan. This operation may be continued for as many times as is deemed necessary.

to effect a complete separation or reclaiming of the unburned fuel from the ashes and upon the completion of the operation the shaft 22 may be slightly rotated in a direction opposite to that indicated by the arrow in Figure 3, thus freeing the arm 34 and clamping element 35 from engagement with the pan in order to permit the same to be readily removed.

10 In the case of certain types of stoves or furnaces it might be necessary to provide a relatively narrow pan of the type shown in Figure 4, and indicated as a whole by the numeral 30, which, when placed in the machine embodying my invention with its adjustable side walls or members 55 arranged vertically in a parallel relation, would be insufficient in width to insure collection of all of the reclaimed material as it leaves the chute 57. In such an event the width of the receptacle, through the instrumentality of the pinions 52 and racks 50 and 51, may be so increased by moving the said members 55 to their respective extended positions that the total width of the receptacle is such as compared with the width of the chute 57 as to effect a depositing of all of the reclaimed material back into the receptacle.

Having thus described my invention I claim:

1. In a device of the character described a rotatable separator unit adapted to receive an ash pan, a rotatable shaft free to partially rotate with respect to said unit, pan locking means operable upon partial rotation of said shaft with respect to said unit to first lock said pan in a given position with respect to said unit and thereafter lock said shaft with respect to said unit, and means for locking said shaft against reverse movement after the same has been so moved as to effect the operation of said pan locking means.

15 2. In a device of the character described a rotatable separator unit adapted to receive an ash pan, a rotatable shaft free to partially rotate with respect to said unit, pan locking means operable upon partial rotation of said shaft with respect to said unit to first lock said pan in a given position with respect to said unit and thereafter lock said shaft with respect to said unit, means for locking said shaft against reverse movement after the same has been so moved as to effect the operation of said pan locking means, and means for releasing the second named locking means upon completion of rotation of said shaft whereby the movement of said shaft with respect to said unit may be reversed to effect a release of said pan locking means.

3. In a device of the character described a rotatable separator unit adapted to receive an ash pan, an operating shaft free to partially rotate with respect to said unit,

means operable upon partial rotation of said shaft with respect to said unit to lock said pan in a given position with respect to said unit and to lock said shaft against rotation with respect to said unit whereby said shaft and unit are caused to rotate together and said pan is caused to move in a circular path, and a brake mechanism adapted to so cooperate with said unit as to resist its rotative movement.

4. In a device of the character described a rotatable separator unit adapted to receive an ash pan, an operating shaft free to partially rotate with respect to said unit, means operable upon partial rotation of said shaft with respect to said unit to lock said shaft against rotation with respect to said unit and to lock said pan in a given position whereby said shaft and unit are caused to rotate together and said pan is caused to move in a circular path, and means adapted to cooperate with said unit to retain the same temporarily in its normal position when at rest.

5. In a device of the character described a rotatable separator unit adapted to receive an ash pan, an operating shaft free to partially rotate with respect to said unit, means operable upon the partial rotation of said shaft with respect to said unit to lock said pan in a given position with respect to said unit and to lock said shaft against rotation with respect to said unit whereby said shaft and unit are caused to rotate together and said pan is caused to move in a circular path, a brake mechanism adapted to so cooperate with said unit as to resist its rotative movement, and means operable upon partial rotation of said shaft for locking the same against rotation in an opposite direction with respect to said unit.

6. In a device of the character described a rotatable separator unit having converging side walls and adapted to receive an ash pan, an abutment for facilitating the proper positioning of said pan within said unit, an operating shaft free to partially rotate with respect to said unit, and means operable upon partial rotation of said shaft with respect to said unit for locking said pan in a given position against said abutment and for locking said shaft against further rotation with respect to said unit whereby said shaft and unit are rotated together and said pan is caused to move in a circular path.

7. In a device of the character described a rotatable separator unit having converging side walls and adapted to receive an ash pan, an abutment for facilitating the proper positioning of said pan within said unit, an operating shaft free to partially rotate with respect to said unit, and means operable upon partial rotation of said shaft with respect to said unit for locking said pan in a given position against said abutment and for

locking said shaft against further rotation with respect to said unit whereby said shaft and units are rotated together and said pan is caused to move in a circular path, and 5 means for resisting the rotative movement of said unit.

8. In a device of the character described a rotatable separator unit having converging side walls and adapted to receive an 10 ash pan, an abutment for facilitating the proper positioning of said pan within said unit, an operating shaft free to partially rotate with respect to said unit, means operable upon partial rotation of said shaft with 15 respect to said unit for locking said pan in a given position against said abutment and for locking said shaft against further rotation with respect to said unit whereby said shaft and unit are rotated together and said 20 pan is caused to move in a circular path, means for resisting the movement of said unit in a given direction, and means for locking said shaft against rotation in an opposite direction with respect to the rotation 25 of said unit.

9. In a device of the character described a rotatable separator unit having converging side walls and adapted to receive an ash pan, an abutment for facilitating the proper 30 positioning of said pan within said unit, an operating shaft free to partially rotate with respect to said unit, means operable upon partial rotation of said shaft with respect to said unit for locking said pan in a given 35 position against said abutment and for locking said shaft against further rotation with respect to said unit whereby said shaft and unit are rotated together and said pan is caused to move in a circular path, means 40 for resisting the movement of said unit in a given direction, means for locking said shaft against rotation in an opposite direction with respect to the rotation of said unit, and means for releasing the latter named 45 locking means upon completion of rotation of said unit.

10. In a device of the character described a rotatable separator unit having converging side walls and adapted to receive an ash pan, 50 an abutment for facilitating the proper positioning of said pan within said unit, an operating shaft free to partially rotate with respect to said unit, means operable upon partial rotation of said shaft with respect to said unit for locking said pan in a given position against said abutment and for locking said shaft against further rotation with respect to said unit whereby said shaft and unit are rotated together and said pan is 55 caused to move in a circular path, means for resisting the rotative movement of said unit, means for locking said shaft against rotation in an opposite direction with respect to the rotation of said unit, means for 60 releasing the latter named locking means 65

upon completion of rotation of said unit, and means for temporarily retaining said unit in a normal position when at rest.

11. In a device of the character described a rotatable separator unit adapted to receive 70 an ash pan, an operating shaft free to partially rotate with respect to said unit, a locking arm carried by said shaft and adapted to be so moved upon partial rotation of said shaft with respect to said unit as to lock said pan in a given position with respect to said unit and to lock said shaft against further rotation with respect to said unit whereby said unit and shaft are caused to rotate together and said pan is caused to move in a circular path. 75

12. In a device of the character described a rotatable separator unit adapted to receive an ash pan, an operating shaft free to partially rotate with respect to said unit, a locking arm carried by said shaft and adapted to be so swung about the axis of said shaft upon partial rotation of said shaft with respect to said unit as to lock said pan in a given position with respect to said unit 80 and to lock said shaft against further partial rotation with respect to said unit whereby said unit and shaft are caused to rotate together and said pan is caused to move in a circular path, a ratchet carried by said 85 shaft, and a pawl adapted to cooperate with said ratchet for locking said shaft against rotation in an opposite direction to the rotation of said unit. 90

13. In a device of the character described a rotatable separator unit adapted to receive an ash pan, an operating shaft free to partially rotate with respect to said unit, a locking arm carried by said shaft and adapted to be so moved upon the partial 100 rotation of said shaft with respect to said unit as to lock said pan in a given position with respect to said unit and to lock said shaft against further partial rotation with respect to said unit whereby said unit and shaft are caused to rotate together and said pan is caused to move in a circular path, a ratchet carried by said shaft, a pawl adapted to cooperate with said ratchet for locking said shaft against rotation in an opposite 105 direction to the rotation of said unit, and means for disengaging said pawl from said ratchet upon the completion of rotation of said unit whereby said shaft is permitted to be partially rotated in an opposite direction to the rotation of said unit to relieve the engagement of said arm with said pan. 110

14. In a device of the character described a rotatable separator unit adapted to receive an ash pan, said unit comprising converging side walls, a screen secured to the outer margin of said side walls, a chute associated with said side walls, an operating shaft free to partially rotate with respect to said unit, a plurality of pan engaging members carried 115 120 125 130

by said shaft and adapted to be moved into engagement with said pan upon partial rotation of said shaft with respect to said unit whereby said unit and shaft are caused to 5 rotate together upon further rotation of said shaft and said pan is caused to move in a circular path, a ratchet carried by said shaft, a pawl adapted to cooperate with said ratchet to lock said shaft against movement 10 in a direction opposite to that of said unit, and means operable upon the completion of rotation of said unit for disengaging said pawl from said ratchet.

15. In a device of the character described a rotatable separator unit having a screening surface associated therewith and adapted to receive an ash receptacle, the screening surface being relatively wide at one end and tapering in width toward the other end, 20 means for retaining said receptacle in a given position with respect to said unit, and means for rotating said unit whereby the contents of said receptacle are deposited upon the screening surface at its relatively wide end and are caused to travel laterally thereover toward the relatively narrow end thereof, the finer material being permitted to pass through said screening surface whereas the relatively coarse material is 25 directed centrally back into said pan over the relatively narrow portion of said screening surface.

16. In a device of the character described a rotatable separator unit having a screening surface associated therewith and adapted to receive an ash receptacle containing ashes, said screening surface being relatively wide at one end and tapered in width towards its other end, said unit comprising converging 30 side walls, said wide walls being attached to said screening area substantially throughout the length thereof, an imperforate chute as-

sociated with said side walls and said screening surface at its relatively narrow end, means for retaining said ash receptacle in a 45 given position with respect to said unit, and means for rotating said unit and receptacle simultaneously about a given axis whereby the contents of said receptacle are deposited upon said screening area at its relatively 50 wide end and are caused to travel laterally thereover, the finer particles of said contents being permitted to pass through said screening surface, whereas the relatively large particles thereof are directed upon the surface of said chute by reason of said converging side walls and are thereafter deposited centrally back into said receptacle over said 55 imperforate chute.

17. In a device of the character described, 60 a rotatable separator unit having a screening surface associated therewith and adapted to receive an ash receptacle, means for rotating said unit, means depending for its operation upon the operation of the first 65 named means for locking said receptacle in a given position with respect to said unit whereby said receptacle is moved bodily with said unit upon rotation of said unit and the contents of said receptacle are deposited 70 upon said screening surface and are caused to move laterally thereover thereby separating the finer particles of said contents from the larger particles thereof, means in the 75 form of converging walls associated with said screening surface for diverting said larger particles toward a given plane passing through said unit perpendicularly to the axis thereof and for directing said larger particles from said unit back into said pan. 80

In testimony whereof, I have affixed my signature to this specification.

WILLIAM C. BROADWELL.
